UNITED STATES PATENT OFFICE.

GRANVILLE E. PALMER, OF CAMBRIDGE, MASSACHUSETTS, ASSIGNOR TO WESTINGHOUSE ELECTRIC & MANUFACTURING COMPANY, A CORPORATION OF PENNSYLVANIA.

CIRCUIT INTERRUPTER.

Application filed March 17, 1924. Serial No. 699,635.

- My invention relates to electrical switching apparatus, and more particularly to a remotely disposed circuit interrupter for alternating-current networks.
- 5 An object of my invention is to provide a remotely disposed circuit interrupter that shall open an alternating-current circuit upon abnormal decrease in potential or failure of current in the circuit.
- 10 Another object of my invention is to provide a circuit interrupter, of the above-indicated character, that shall be closed by a series of electrical and mechanical operations consequent to the operation of a remotely disposed switch.

A further object of my invention is to provide a circuit interrupter that shall be locked in its closed position by mechanical means which is adapted to be released when

20 the voltage in the circuit falls below a predetermined value.

My invention is an improvement over the low voltage circuit interrupter shown and described in my prior Patent No. 1,179,957, 25 patented April 18, 1916, and a low voltage circuit breaker shown and described in the patent to Johnson, No. 1,431,956, issued October 17, 1922, both of which are assigned to the Westinghouse Electric & Manufacturing Company.

In the accompanying drawings,

Figure 1 is a front elevational view of a circuit interrupter embodying my invention.

Fig. 2 is a side elevational view thereof.

Fig. 3 is a view of my circuit interrupter taken along the section line III—III of Fig. 1 and also showing in dot and dash lines an additional operating detail lying in front of that section line, the closed position of the circuit interrupter being shown in full lines and the open position being shown in broken lines.

Fig. 4 is a view, partially diagrammatic and partially perspective, of apparatus and circuits embodying my invention.

In the several figures of the drawing, the same reference numerals indicate similar parts.

In my invention, I provide a circuit interrupter comprising a base member 1, a solenoid 2 mounted thereon and having a movable core member 3 and a lever arm 4 that is actuated thereby. The arm 4, which is pivotally mounted on a shaft 5, supports

a cross-bar 6, which in turn supports a pair 55 of movable members 7 and 8. The members 7 and 8 are of rectilinear form and are severally provided with main contact brushes 9 and 11 and arcing contact members 13 and 14.

60 Stationary contact members 15 and 16 are mounted on the base member 1 for co-operation with the brush 11 and arcing contact member 14 and brush 9 and arcing contact member 18, respectively. It is to be observed that the engaging surfaces of the stationary contact members 15 and 16 are disposed in planes substantially at right-angles to each other.

The arm 4 is pivotally secured to the movable core member 3, as at 17, and is provided adjacent to its upper end with a slot 18, in which a latch member 19 is pivotally mounted on a shaft 21. The latch member 19 is provided with a notch 22 and a tail-piece 23, which terminates in a projection 24.

70 A bracket 25 is secured to the base member 1 and it forms a support and magnetizable housing for the solenoid 2, and a support for a projection 26 of U-shape that extends into the slot 18. The latch 19 is adapted to ride over the cross-piece 26, and the notch 22 is adapted to fall over it when the arm 4 is in the closed position of the circuit interrupter.

75 An arm or bell-crank lever 27 is pivotally mounted, as at 28, on the bracket 25. The inner end of the arm 27 terminates in a weight 29 that has a projection 31 extending from one corner thereof. The other end of the arm 27 terminates in a plate or cam 32, which extends outwardly beyond and to the left of lever arm 4 for engaging a pin 26^a thereon during the closing operation of the circuit interrupter. A projection 33 extends upwardly from the arm 27 at a point adjacent to the pivot 28.

80 A bracket 35 is secured to the base member 1 and pivotally supports a bell crank lever 36 comprising arms 37 and 38 and a latch 39, the latter co-operating with the projection 31 on the weight member 29. A spring 41 is so disposed as to bias the bell crank lever 36 in a counter-clockwise direction. It will be observed that the arm 37 85 and the latch 39 extend in a vertical direction while the arm 38 extends in a horizontal direction. A pair of solenoids or trip coils

42 are disposed above the arm 38 of the lever 36 in such manner that its weighted armature 43 impinges upon the arm 38 when released by the solenoids 42. The armature 43 carries a bridging member 44 which closes the circuit between stationary contact members 45 and 46 when the armature 43 is in its raised position.

A pawl 48 is secured by a shaft or pin 49 to the bracket 25, and is biased in a counter-clockwise direction by a spring 51 that is coiled about the shaft 49. The lower edge of the pawl 48 rests between the projection 24 on the latch 19 and the projection 33 on the arm 27, when the circuit interrupter is in its closed position.

The lower end of the arm 4 is in the form of a yoke 61, to which an extending lug 62 is secured. A lever 63 is pivotally mounted 20 on the shaft 5 and is adapted to be moved by the yoke member 61 when the arm 4 moves from its open to its closed position. The outer end of the lever 63 is provided with a notch 64, and an extension 65 is attached 25 near the other end by means of a pintle 66 and a spring 67.

A bridging member 68 is carried at the free end of the extension 65, and is adapted to engage a pair of stationary contact members 69 when the circuit interrupter is in its open position, and to rest against stop members 71 when the circuit interrupter is in its closed position. A spring 72 is mounted on the shaft 5 and tends to normally bias the 30 lever 63 in a counter-clockwise direction or to its circuit-interrupting position. A latch 75 is pivotally mounted, on a pin or shaft 76, and is biased by a coil spring 77 into engagement with the notch 64 of the lever 63 when the circuit interrupter is in its open 35 position.

A bracket 78 secures a member 79 of insulating material to the lower face of the yoke 61. A pair of bridging members 81 are mounted on the insulating member 79 and are adapted to engage stationary contact members 82 when the circuit interrupter is in its open position. The bridging members 81 and stationary contact members 82 may 40 be placed in circuit with a pilot lamp, alarm bell or any other desired indicating means.

A fuse 83 that is in circuit with the solenoids 42, is secured by clips 84 to the base member 1.

In Fig. 4, a supply circuit of relatively low voltage is indicated at 91. This circuit extends from the stationary contact member 15 of the movable members 7 and 8, through the stationary contact members 16 to any desired electrical translating apparatus. It will thus be seen that the movable contact members 9 and 11 are connected directly in series with the circuit under control.

A second circuit extends from the terminal 94, that is connected to one conductor of the

circuit 91, through a switch 95, which may be located at any remote point, the solenoids 42, and to a terminal 96 which is connected to the other conductor of the circuit 91. A third circuit extends from a terminal 97, 70 in one conductor of the supply circuit 91, through the stationary contact members 69, the bridging member 68, solenoid 2, stationary contact member 45, 46, and the bridging contact 44, to a terminal 98 in the other 75 conductor of the supply circuit 91.

It is to be observed that the second circuit is completed upon the closing of the switch 95, and that the solenoids 42 are normally energized at all times. The third 80 circuit is completed only when the bridging member 68 is in engagement with the stationary contact members 69 and the bridging contact member 44 is in engagement with the stationary contact members 45 and 46. 85

In order to operate my improved switching device from the open position shown in dotted lines of Fig. 3, to the closed position shown in Figs. 1, 2 and 4, the operator closes the switch 95, whereupon the solenoids 42 90 become energized and the circuit is completed between the stationary contact members 45 and 46 by the bridging member 44 that is mounted on the armature 43. As is shown in Fig. 3, the lever 63 and the extension 65 are 95 so disposed as to close the circuit through the stationary contact member 69 and the bridging member 68, when the lever 4 is in its circuit-interrupting position.

When the circuit is completed between the stationary contact members 45 and 46, the solenoid 2 is energized and exerts a force upon its armature member 3, which in turn is transmitted to the arm 4 and the movable members 7 and 8, causing them to turn in a counter-clockwise direction about the shaft 5. As the arm 4 turns to the left, as shown in Fig. 3, the tail-piece 23 of the latch 19 engages the plate 32 of the arm 27, causing the latch 19 to turn in a clockwise direction about its pivot 21, and causing the lever 27 to turn in a clockwise direction about its pivot 28. This movement is continued until the tail-piece 23 of the latch 19 passes over the bracket 26, and the notch 22 is in place. At the same time, the weight member 29 is raised by the lever 27, and the projection 31 thereon is retained by the latch 39. During this movement the pawl 48 is pushed to the left by the projection 24 on the latch 19, and thereafter moves over and drops behind this projection in front of the projection 33 on the arm 27. The spring 51 so biases the pawl 48 into this position, that the latch 19 is normally held in contact with the bracket 26 110 by reason of the engagement of the pawl 48 with the projections 24 and 33. 115

As the arm 4 reaches the end of its travel, the projection 62 bears against the latch 75 120 in opposition to the tension of the spring 77 130

causing the latch 75 to be disengaged from the notch 64, whereupon the third circuit is interrupted by reason of the action of the spring 72 in separating the stationary contact members 69 and the bridging member 68. The interruption of the circuit between the stationary contact members 69 and bridging member 68 serves to de-energize the solenoid 2 while the movable members 7 and 8 remain in their circuit closing position.

In the case of excessive voltage drop in the circuit 91, the solenoids 42 become de-energized to such degrees that the weighted armature 43 moves downwardly under the influence of the force of gravity, at the same time separating the stationary contact members 45, 46 and the bridging contact member 44. The armature 43 falls upon the arm 38 with sufficient force to compress the spring 41 and disengage the latch 39 from the weight member 29, whereupon the arm 27 is turned in a counter-clockwise direction about its pivot 28, and the projection 33 turns the pawl 48 in a clockwise direction against the tension of the spring 51. This action permits the projection 24 on the latch 19 to move from under the pawl 48, and the notch 22 is disengaged from the bracket 26, whereupon the arm 4 and the movable members 7 and 8 are caused to move in a clockwise direction about the pivot 5 by reason of the inherent resiliency of the brushes 9 and 11, together with the force of gravity, and if desired, also by a spring mounted on the shaft 5 to the open position shown by broken lines in Fig. 3. During the circuit-interrupting movement, the yoke 61 engages the arm 63 to cause the latter to complete the circuit between the stationary contact member 69 and the bridging contact member 68 in which position it is held by the engagement between the notch 64 and the latch 75.

In the event that the operator desires to interrupt the circuit through the moving contact members 9 and 11, he interrupts the circuit at the switch 95, which results in the de-energization of the solenoids 42 and the resultant tripping of the members 7 and 8.

It will thus be seen that I have provided a switching device which is held in its closed position by reason of a normally energized circuit. It is also to be observed that the circuit of the main operating solenoid 2 is interrupted when the switch reaches its closed position, and at another point when the voltage in the circuit under protection falls below a predetermined value.

It is to be understood that such changes may be made in the apparatus and circuits herein shown, as fall within the scope of the appended claims.

I claim as my invention:

1. A switch mechanism comprising a movable member having contact members thereon, a solenoid for actuating the movable

member to closed position of the switch, means tending to actuate the movable member to open the switch, a stationary bracing member, a pivoted member supported on the movable member and provided with a recess adapted to coincide with the bracing member when the switch is in closed position, a latching member disposed to engage the pivoted member to hold it against the bracing member, and electromagnetically-controlled means for controlling the latching member.

2. A switch mechanism comprising a movable member having contact members thereon, a solenoid for actuating the movable member to closed position of the switch, means tending to actuate the movable member to open the switch, a stationary bracing member, a pivoted member supported on the movable member and provided with a recess adapted to coincide with the bracing member when the switch is in closed position, a latching member disposed to engage the pivoted member to hold it against the bracing member, gravity-actuated means for controlling the latching member to release the pivoted member, and an electromagnetically-controlled member for controlling the gravity-actuated means.

3. A switch mechanism comprising a movable member having contact members thereon, a solenoid for actuating the movable member to closed position of the switch, means tending to actuate the movable member to open the switch, a stationary bracing member, a pivoted member supported on the movable member and provided with a recess adapted to coincide with the bracing member when the switch is in closed position, a latching member disposed to engage the pivoted member to hold it against the bracing member, a gravity-actuated means for controlling the latching member to release the pivoted member, a supporting member normally restraining movement of the gravity-actuated means, and an electromagnetically-controlled member for rendering the supporting member ineffective.

4. Switch mechanism comprising a stationary member, a movable member, a pivoted member on the movable member for engaging the stationary member, a spring-controlled latch for maintaining the pivoted member in effective engagement with the stationary member to preclude movement of the movable member and a pivoted weight member for increasing the effectiveness of the spring-controlled latch.

5. Switch mechanism comprising a stationary member, a movable member, a pivoted member mounted on the movable member adapted to engage the stationary member when the movable member is in a predetermined position, a spring-controlled pivoted member for maintaining the first-mentioned

5 pivoted member in effective engagement with the stationary member to preclude relative movement therebetween, and an electro-magnetically-controlled weight for increasing the effectiveness of the spring-controlled pivoted member.

6. Switch mechanism comprising a stationary member having a curved contour, a 10 movable switch-controlling member, a pivoted member secured to the movable member and provided with a curved notch having a contour corresponding to that of the stationary member and adapted to engage the same when the movable member is 15 in the closed position of the switch, latching means for maintaining the pivoted and the stationary members in engagement to preclude relative movement therebetween, a gravity-actuated member for actuating the 20 latching means to release the movable member and means for actuating the movable member to open-switch position.

7. Switch mechanism comprising a movable switch supporting member, a stationary 25 bracing member, holding means co-operating with the stationary member and the movable members to preclude movement of the movable member, a weight for rendering said means ineffective, a latch for normally maintaining the weight in raised position, means 30 for actuating the latch to release the weight to permit movement of the movable member, and means controlled by the movable member for resetting the weight in operative 35 position.

8. Switch mechanism comprising a movable switch supporting member, a stationary 40 bracing member, holding means co-operating with the stationary member and the movable members to preclude movement of the movable member, a weight for rendering said means ineffective, a latch for normally maintaining the weight in raised position, 45 electromagnetically-controlled means for actuating the latch to release the weight and thereby render the holding means ineffective, and means controlled by the movable member for resetting the weight in operative position before the holding means are again 50 rendered effective.

9. Switch mechanism comprising a movable switch member, a holding means therefor comprising a latch, means comprising a weight for rendering the holding means ineffective by actuating the latch, and means controlled by the movable member for resetting the weight.

10. Switch mechanism comprising a movable switch member, a holding means therefor comprising a latch, means comprising a weight for rendering the holding means ineffective by actuating the latch, a holding device for the weight comprising a spring-controlled pivotally-mounted member, electro-magnetic means for controlling the

operation of the holding device, and means controlled by the movable member for resetting the weight.

11. Switch mechanism comprising a movable switch member, a holding means therefor comprising a latch, means comprising a weight for rendering the holding means ineffective by actuating the latch, a holding device for the weight comprising a spring-controlled pivotally-mounted member, electro-magnetic means for controlling the operation of the holding device, upon being de-energized, and means for resetting the weight upon the re-energization of the electromagnet. 70

12. Switch mechanism comprising a movable switch member, means comprising a latch for holding the movable member in switch-closing position, a weight for rendering the latch ineffective and permitting the movable member to move to open position, a spring-controlled pivoted latch for normally holding the weight in operative position, an electromagnet, a movable member controlled thereby for rendering the latch ineffective in holding the weight and means for resetting the weight after opening the switch but before reclosing the same. 85

13. Switch mechanism comprising a movable switch member, means comprising a latch for holding the movable member in switch-closing position, a weight for rendering the latch ineffective and permitting the movable member to move to open position, a spring-controlled pivoted latch for normally holding the weight in operative position, an electromagnet, a movable member controlled thereby for rendering the latch ineffective in holding the weight upon the de-energization of the electromagnet, and means for resetting the weight upon the re-energization of the electromagnet. 95

14. Switch mechanism comprising a movable switch member, means for holding said member in switch-closing position, gravity-actuable means for rendering the holding means ineffective, means for then moving the switch member to open position, and means controlled by the movable member for resetting the gravity-actuable means for a subsequent operation. 110

15. Switch mechanism comprising a movable switch member, means for holding said member in switch-closing position, gravity-actuable means for rendering the holding means ineffective, means normally holding the gravity-actuable means in operative position, means tending to move the switch member to open position and operative after the holding means is rendered ineffective, an electromagnet, means controlled thereby for effecting the release of the gravity-actuable means and means controlled by the electromagnet for resetting the gravity-actuable means. 120

16. Switch mechanism comprising a movable switch member, means for holding said member in switch-closing position, gravity-actuable means for rendering the holding means ineffective, means normally holding the gravity-actuable means in operative position, means tending to move the switch member to open position and operative after the holding means is rendered ineffective, an electromagnet, means controlled thereby, for 10 effecting the release of the gravity-actuable means, and means controlled by the movable-member for resetting the gravity-actuable member.
